ABSTRACT OF THE DISCLOSURE

An electron discharge device modifies an input signal in accordance with a desired transform function. The input signal sweeps an electron beam over a first anode which has a shape conforming to the integral of the transform function. A portion of the electron beam, determined by the shape of the first anode, passes to a second anode to produce an output signal on the anodes. The output signal is the product of the input signal and the transform function.

This invention relates to electron discharge devices, and particularly, to an electron discharge device for modifying an input signal in accordance with a desired transform function.

An object of this invention is a new and improved electron discharge device.

Another object of this invention is an electron discharge device having an element with a mathematically derived dimension which may be fabricated to perform one of a plurality of functions.

A further object of this invention is a new and improved broad-band amplifier.

An additional object of this invention is a new and improved broad-band frequency multiplier.

A still further object of this invention is a new and improved broad-band frequency divider.

In accordance with these and other objects, an embodiment of the invention produces an output signal equal to an input signal multiplied by a transform function. An input signal sweeps an electron beam over a first anode which has a shape conforming to the integral of the transform function. A portion of the electron beam determined by the shape of the first anode passes to a second anode to produce an output signal on the anodes.

A complete understanding of the invention may be had by reference to the following detailed description when considered in conjunction with the accompanying drawings, wherein:

FIG. 1 is a schematic of a broad-band amplifier embodying the invention;

FIGS. 2 and 3 show alternate anodes which may be substituted for an anode shown in FIG. 1 to produce a frequency doubler and frequency tripler, respectively; and

FIG. 4 shows an alternate anode and circuitry which may be substituted for an anode shown in FIG. 1 to produce a frequency divider.

An electron discharge device has two consecutive anodes 11 and 12 interposed in the path of a horizontal fan-shaped electron beam 13 within an evacuated enclosure (not shown). The first anode 11 has an opening 14 (FIG. 1) through which a portion of the beam 13 passes to the second anode 12. The beam 13 is generated by a negative electron source 16 and spread into a substantially constant density horizontal fan shape by the electrostatic field produced by positively biased electrodes 17. An input signal 18 applied to deflection plates 19 controls the vertical positioning of the beam 13. An output signal 21 is produced across resistors 22 and 23 which

2

connect the respective anodes 11 and 12 to a ground potential.

If the input signal 18 is F_i and the output signal 21 is F_o , then $F_o = F_i \times F_t$ where F_t is a transform function. The shapes of the sides 24 of the opening 14 conform to the integral of the transform function F_t and the width of the opening 14 conforms to a complement of that integral.

In a linear amplifier, $F_o = F_i \times K$ where K is the amplification constant. The integral of K is a function which increases linearly, and thus, the apparatus in FIG. 1 is a broad-band amplifier because of the linearly decreasing width of the opening 14 for increasing input signals. This broad-band amplifier will amplify signals having a frequency range from zero frequency to an upper frequency determined by the capacitance of the deflection plates 19 and transit time of electrons between the plates 19. An amplifier with a desired nonlinear response may be fabricated by making the sides 24 of the opening nonlinear. Also, if the density of the fan-shaped beam 13 is not constant throughout its width, the sides 24 may be made nonlinear to compensate for the nonconstant density.

The anode 11 may be fabricated with (1) a contoured side 26 (FIG. 2) to produce a frequency doubler for a sinusoidal input signal, (2) an opening 27 (FIG. 3) to produce a frequency tripler for a sinusoidal input signal, or (3) an opening 28 (FIG. 4) to produce an output signal which may be changed into a signal having a frequency which is one-half the frequency of a sinusoidal input signal. The shape of the side 26 and the shapes of the sides of the openings 27 and 28 conform to respective integrals of corresponding transform functions. Other shapes of the anode 11 may be made in conformity to the integration of transform functions to produce desired output signals.

In a frequency doubler, $\sin 2X = \sin X \times 2 \cos X$ where $F_o = \sin 2X$, $F_i = \sin X$ and $F_t = 2 \cos X$. The integral of $2 \cos X$ equals $2 \sin X + C$. Thus, in FIG. 2, the shape of the side 26 along a vertical axis conforms to $\sin X$.

In a frequency tripler, $\sin 3X = \sin X \times (3 - 4 \sin^2 X)$ where $F_o = \sin 3X$, $F_i = \sin X$ and $F_t = 3 - 4 \sin^2 X$. The integral of $3 - 4 \sin^2 X$ equals $X + \sin 2X + C$. Thus, in FIG. 3, the shape of one side of the opening 27 along a vertical axis conforms to $X + \sin 2X$.

In a frequency halver,

$$\sin \frac{X}{2} = \pm \sin X \times \sqrt{\frac{1 - \cos X}{2 \sin X}}$$

wherein

$$F_o = \sin \frac{X}{2}, F_i = \sin X, \text{ and } F_t = \sqrt{\frac{1 - \cos X}{2 \sin X}}$$

The integral of

$$F_t \text{ equals } \ln \left(\sec \frac{X}{2} + \tan \frac{X}{2} \right)$$

Thus, in FIG. 4, the shape of the side of the opening 28 along a vertical axis conforms to the integral of F_t .

In both the frequency doubler and the frequency tripler, the output signal consists of only the desired sinusoidal harmonic. The input frequency and any harmonic frequencies other than the desired harmonic are small enough that they would have no adverse effect in most applications of the doubler and tripler. The frequency doubler and tripler multiply frequencies within the range from a small value approaching zero to a frequency determined by the capacitance of the deflection plates 19 and the transit time of electrons between the plates 19. However, the input signal must have a predetermined amplitude so that the beam 13 will sweep

from the lower ends of the side 26 and opening 27 to the upper ends of the side 26 and opening 27.

In FIG. 4, the anode 11 with the opening 28 is connected to ground potential and the anode 12 is connected by a resistor 31 to ground potential. The signal 32 produced on the anode 12 conforms to a full-wave rectified signal which may be changed into a sinusoidal signal 41 having a frequency which is one-half the frequency of the input signal 18.

The signal 32 is applied to the input of a paraphase amplifier 33 which produces two signals 34 and 35 which are complementary. The signals 34 and 35 are applied to respective gates 37 and 38 which are alternately operated by a bistable multivibrator 39 to alternately pass one of the signals 34 or 35 to a common output. The signal 35 is applied to an input of the multivibrator 39 to switch the multivibrator to alternate states every cycle of the signal 35 to operate the gates 37 and 38. Alternate cycles of the respective signals 34 and 35 pass through the gates 37 and 38 to produce the sinusoidal output signal 41 having a frequency which is one-half the frequency of the input signal 18.

It is to be understood that the above-described embodiments are illustrative of the principles of the invention and that many other embodiments could be devised without departing from the scope of this invention.

What is claimed is:

1. An electron discharge device for producing an output signal equal to an input signal multiplied by a transform function, which comprises:

means for producing an uninterrupted electron beam; a first anode having a shape substantially conforming to the integral of the transform function and upon which a first portion of the electron beam impinges; a second anode located behind the first anode in the path of the electron beam and upon which an unobstructed portion of the electron beam impinges; and

means for deflecting the electron beam in accordance with the input signal to produce the output signal on one of the anodes, said electron beam impinging on a first area of the first anode and a second area of the second anode, said first and second areas having a dimension conforming to the shape of the first anode.

2. An electron discharge device as defined in claim 1, wherein:

the electron beam is fan shaped; the first anode has an opening wherein a side of the opening conforms to the integral of the transform function and upon which the first portion of the electron beam impinges.

3. An electron discharge device as defined in claim 1, wherein:

the shape of the first anode is varied to compensate for nonlinearity of the electron beam.

4. A broad-band amplifier including the elements of claim 1, wherein:

the electron beam is fan shaped; and

the first anode has a linearly increasing dimension upon which the first portion of the electron beam impinges.

5. A frequency multiplier including the elements of claim 1, wherein:

the input signal is sinusoidal; the electron beam is fan shaped; and the first anode has an opening wherein a side of the opening conforms to the integral of the transform function and upon which the first portion of the electron beam impinges.

6. A frequency divider comprising the elements of claim 1, wherein the input signal is sinusoidal and the deflecting means produce an output signal which is changed by the following elements into a signal having a frequency which is one-half the frequency of the input signal:

a paraphase amplifier having an input connected to one of the anodes for producing two complementary signals on respective outputs of the amplifier; and means connected to the respective outputs of the amplifier for alternately passing cycles of the complementary signals to a terminal to produce the sinusoidal signal having a frequency which is one-half the frequency of the input signal.

7. A frequency divided as defined in claim 6, wherein the alternately passing means comprises:

a first gate connected between a first output of the amplifier and the terminal; a second gate connected between the second output of the amplifier and the terminal; and a bistable multivibrator having an input connected to the first amplifier output and having respective outputs connected to the first and second gates for alternately operating the first and second gates every cycle of the signal on the first amplifier output to alternately pass cycles of the complementary signals to the terminal to produce a sinusoidal signal having a frequency which is one-half the frequency of the input signal.
